UNITED STATES PATENT OFFICE.

ALFRED H. WILLETT, OF WEST NEW YORK, NEW JERSEY, ASSIGNEE, BY ASSIGNMENT, TO AMERICAN ARCH COMPANY, OF NEW YORK, N. Y., A CORPORATION OF DELAWARE.

LOCOMOTIVE BAFFLE-WALL.

1,143,095.

Specification of Letters Patent. Patented June 13, 1916.

Application filed August 24, 1914. Serial No. 358,167.

To all whom it may concern:

Be it known that I, ALFRED H. WILLETT, a citizen of the United States, residing at West New York, in the county of Hudson 5 and State of New Jersey, have invented certain new and useful Improvements in Locomotive Baffle-Walls, of which the following is a specification.

This invention relates to locomotive fire- 10 box baffle walls, and has particular reference to the arch bricks supported on the circulation tubes to constitute such walls.

In standard forms of fire-box construction the baffle walls or arches are composed of 15 several rows of arch bricks supported on the circulation tubes and the side sheets, each row preferably being composed of at least several bricks. The distance between the circulation tubes varies on different locomotives, and not infrequently tubes on the 20 same locomotive are not equidistant. As a result of this, difficulty has been encountered in providing an arch brick which will readily adapt itself to such varying conditions, 25 and it is one of the chief objects of my invention to provide a novel form of arch brick which can be used on tubes the spacings of which vary. Still another object of the invention resides in the provision of an 30 improved brick which, in addition to having the characteristics just set forth, can still be readily reversed. The foregoing, together with such other objects as may hereinafter appear or are incident to my invention, I attain by means of a construction illustrated 35 in preferred form in the accompanying drawings, wherein,

Fig. 1 is a horizontal sectional view of a portion of a locomotive fire box showing my 40 improved construction. Fig. 2 is a section taken on the line II--II of Fig. 1. Fig. 3 is a perspective view of a brick embodying my improvements; and Figs. 4 and 5 are enlarged views, showing the relative arrangement of adjacent bricks on tubes having a minimum and a maximum spacing, respectively.

Referring now to Figs. 1 and 2, particularly, it will be seen that I have shown a 45 standard type of fire box, comprising an inner fire box composed of a tube sheet 1, side sheets 2, back sheet 3, and crown sheet 4, and an outer box comprising a throat sheet 1^a, outside side sheets 2^a, and an outside back

sheet 3^a. The water legs are closed by the 50 usual mud ring 5, and the front and rear legs are connected by rearwardly and upwardly extending circulation tubes 8, in this case three in number. The baffle wall or arch A is supported on the tubes and extends from a point adjacent the tube sheet a portion of the distance to the rear of the firebox.

Referring now to the arch A, it will be noted that, in the type shown, the arch comprises a middle or central wall composed of two rows of arch bricks 9, usually termed middle bricks, and two end walls or wings each composed of a row of bricks 10. The middle bricks 9 are supported on the arch 70 tubes, and the wing bricks are supported at one end on a circulation tube and engage a side sheet at the other end.

The construction of the middle bricks is shown in preferred form in Figs. 3, 4 and 5, from inspection of which it will be seen that on the lower side, the bricks are provided at one end with an inclined or beveled surface 11 and at the opposite end with a socket 12, while on the upper side they are provided at 75 opposite ends with inclined or beveled surfaces 13 somewhat in the nature of sockets.

By providing the inclined or beveled surfaces at the ends, the bricks accommodate themselves to different spacings of the circulation tubes, because such surfaces will slip or ride on the tubes, as will be clear from inspection of Figs. 4 and 5. An additional range of adjustment to fit the tubes is obtained by making the distance between the surfaces 13 greater than the distance between the surfaces 11 and sockets 12. It will be noted that where there is a minimum or narrow spacing of the tubes, the bricks ride well up on the tubes, thus bringing the 90 ends of the bricks toward one another, while if the spacing is greater, the ends of the bricks will be separated, as shown for example in Fig. 5. Bricks having a maximum span will be required for the larger spacings, but such bricks are obviously not suitable to the smaller spacings. My invention contemplates the provision of a brick having a maximum span which is, nevertheless, adapted to fit tubes having relatively narrow spacings. I accomplish this by so forming the bricks that they are free to slide or extend past each other at the ends, the pre-

ferred arrangement being as follows: At one end, preferably opposite to the end having the socket 12, the bricks are provided with interfitting protuberant portions or corrugations 14, which are so arranged that any of the bricks can still be reversed and be capable of shifting to interfitting relation. Where the tubes are spaced a minimum distance apart the corrugations project, in interlocked or interfitting relation, past each other, as shown in Fig. 4, the bricks should be of such length that their adjacent ends are out of contact so as to permit the removal of one brick without disturbing the other. Where there is a larger spacing of the tubes, the bricks are supported on the tubes in the manner shown in Fig. 5, that is, the corrugations do not interlock.

An additional advantage resides in the fact that when the bricks are reversed a further range of adjustment is provided as previously pointed out and it will be apparent that the bricks readily accommodate themselves to irregularities in the tubes themselves as well as in their arrangement, and that they, nevertheless, seat themselves firmly. Chipping of the bricks is also practically eliminated and the manufacture is simplified and cheapened because of the fact that the number of sizes necessary is greatly reduced. In the drawings I have shown the preferred embodiment of my invention only, and my invention is not limited to the exact arrangement shown and described.

35. What I claim is:

1. A locomotive arch brick having a corrugated support-engaging end, whereby when a plurality of the bricks are assembled in an arch structure the bricks accommodate themselves to varying distances between points of support.
2. A locomotive arch comprising in combination a plurality of independently supported arch bricks, and supports therefor, said bricks having interfitting means extending in substantially the same horizontal plane whereby said bricks accommodate themselves to varying distances between points of support.
3. A locomotive arch comprising in com-

bination a plurality of independently supported arch bricks, and supports therefor, said bricks having protuberant portions at an extremity adapted to extend past each other in substantially the same horizontal plane whereby the bricks accommodate themselves to varying distances between points of support.

4. A locomotive arch brick having a tube-engaging end provided with an offset protuberant portion, so formed and arranged that when a plurality of the bricks are assembled the said portions are adapted to extend past each other in substantially the same horizontal plane and adapt the bricks to supports spaced apart varying distances.

5. A locomotive arch brick having a serrated end, whereby, when a plurality of the bricks are assembled the serrated ends are adapted to extend past each other and adapt the bricks to fit varying distances between points of support.

6. A locomotive arch brick having at an edge an offset protuberant portion so formed and arranged that when a plurality of bricks are assembled in an arch structure the protuberant portions at the edges of the bricks extend past each other in substantially the same horizontal plane to accommodate the bricks to spans of the arch structure of varying dimensions and to permit the bricks to be supported independently of one another.

7. A locomotive arch comprising in combination a plurality of arch brick supporting members, and a plurality of arch bricks independently supported on said members, each brick having a protuberant portion at one edge adapted to interfit with and extend past the corresponding portion of the adjacent brick in substantially the same horizontal plane whereby said bricks may be accommodated to spans of the arch of varying dimensions.

In testimony whereof, I have hereunto signed my name in the presence of the two subscribed witnesses.

ALFRED H. WILLETT.
